UNITED STATES PATENT OFFICE.

STEPHEN G. WRIGHT, OF CHICAGO, ILLINOIS.

MANUFACTURING ARTIFICIAL SHINGLES.

Application filed July 12, 1924. Serial No. 725,856.

The present invention relates to the manufacture of vari-colored asphalt shingles, slabs, etc., and will be fully understood from the following description, illustrated by the accompanying drawings, in which—

Figure 1 is a diagrammatic view of apparatus suitable for carrying the invention into effect, and

Figure 2 shows diagrammatically a portion of the sheet produced in accordance with the present invention prior to cutting into shingle sizes.

In the manufacture of asphalt slabs, shingles, etc., which are produced by depositing grit of the desired color upon asphalt coated felt, it has become desirable to produce the shingles or slabs in a variety of colors such that shingles or slabs selected at random may be laid on a roof and produce a properly blended array of colors without marked contrasts. In accordance with the present invention, shingles, etc., are produced in a variety of colors, without affecting the continuity of the manufacturing process and the resulting shingles are of such a character that their colors blend properly when selected at random and laid.

The manufacturing process is illustrated diagrammatically in Figure 1 of the drawings. The numeral 5 indicates a saturating tank filled with melted saturating asphalt through which the felt is passed in a continuous band. The felt is indicated by the numeral 6. From the saturating tank the saturated felt passes between rolls 7, which squeeze out the excess of pitch, and from these the felt passes under the asphalt distributing nozzles 8 and spreading roll 9, by which the asphalt coating on the felt is evenly applied and distributed. Before the asphalt coating cools, the felt passes under the grit hopper 10, by which the grits are applied to the surface of the felt in a substantially uniform layer. The coated felt then passes between the pressure rolls 11, by which the grit is forced into the hot asphalt coating. The felt is then carried by rolls 12 over a bin 13, into which surplus grit, not held by the asphalt layer, is dropped. The coated felt then continues in its travel to the cooling rolls 14, and thence to the festooners 15, the cooling of the felt being completed while traveling over the latter. The cooled felt is then carried to the cutting table 16, the coated felt being cut to shingle form by the cutters 17.

In the process of manufacture of the shingles, etc., it will be noted that the process is continuous throughout, and it is important that its continuity shall not be interrupted in the manufacture of shingles or roofing of varying colors. In carrying out the present invention, grits of different colors are employed for forming the vari-colored shingles. In order that the invention may be clearly understood, it will be described first in connection with the use of two contrasting colors, for example, red brick and slate blue.

In carrying out the invention, the distributing hopper 10 is first supplied with the desired quantity of grit of one of the colors; for example the red brick. As the asphalt coated felt travels below the hopper 10, the grit thus supplied is distributed over a predetermined area of the continuously moving felt. As the supply for coating this predetermined area of felt approaches exhaustion, the hopper 10 is supplied with a suitable quantity of a blend of grit of substantially the two contrasting colors which are to be employed; in this case, the red brick and the slate blue. As indicated in Figure 2, the supply of grit of the first mentioned color forms an area 18 of substantially solid color. The supply of blended grit forms a succeeding area of predetermined size 19, of the blended color. Between the two areas 18 and 19 is a smaller area 20, formed during the period the supply of the first color is being exhausted and the supply of blended color is beginning its distribution, this small area verging toward the solid color in tone. As the supply of blended color approaches exhaustion, the distributing hopper 10 is supplied with the contrasting color (slate blue for example), and this forms an area of predetermined size designated by the numeral 21. Between the areas 19 and 21 is formed an intermediate small area 22 during the period in which the supply of blended color is being exhausted and the supply of the contrasting color is beginning its distribution. The operation may be repeated after the supply of the second color (slate blue) is exhausted, a blend of that color with some contrasting color, grit being employed, the contrasting color being, for example, buff. The blends may be made up of the colors of grit used in forming the solid color portions or of grit having substantially similar

color values. Any desired number of colors and blends may be employed, the number of possible blends being determined by the number of combinations of the colors used 5 taken two at a time. Thus, with two colors, one blend is possible. With three colors, three blends may be formed; with four colors, six blends may be formed, and so on. Any number of these contrasting colors and 10 of the blends thereof may be employed, as desired, the interval between any two successive contrasting colors being filled by grit of a blend of substantially those colors. If desired, a number of varying blends of 15 colors in different proportions may be interposed between the portions made up of the component colors.

In carrying out the operation, the various grits and blends of grit to be used will be 20 supplied to the operator in predetermined quantity and in a predetermined order. The quantity of grit supplied determines the area of felt to be covered and likewise the number of shingles of the color 25 or blend of colors which will be formed. Thus, a certain number of bags of grit of a predetermined color will be supplied the operator and marked with a certain identifying mark, say the numeral 1. These 30 will be used by the operator, and, as they are exhausted, he will have provided him a certain number of bags of a blend of substantially that color and the contrasting color of grit next to be employed, these bags being 35 marked, for example, with the numeral 2 to indicate that they are to be used next in sequence. The grit of the contrasting color which are to follow these of the blended color will be marked, for example, with the 40 numeral 3 to indicate the order in which they are to be used. Similarly, the successive blends and solid colors of grits may be suitably marked to indicate the sequence in which they are to be used. 45 As the felt is formed in the manner described, it is cut into shingles by the cutters 17, and the shingles thus formed are selected either according to the succession in colors or at random and packed in the usual 50 manner. As the shingles from the packs are laid at random in forming a roof, the various contrasting colors and blends of

colors form a pleasingly blended and varicolored roof, without objectionable or violent contrast in color at any point. 55

Although the present invention has been described in connection with the specific details of a method of carrying it into effect, it is not intended that these details shall be regarded as limitations upon the scope of 60 the invention except in so far as included in the accompanying claims.

I claim:

1. The method of preparing roofing for the manufacture therefrom of vari-colored shingles etc. comprising applying to an asphalt coated felt in longitudinal sequence over successive predetermined areas, first, grit of a defined color; second, grit of a blend of substantially said defined color and a contrasting color; and next, grit of substantially the contrasting color; and subsequently subdividing the coated felt to form shingles. 65 70

2. The method of preparing roofing for the manufacture therefrom of vari-colored shingles etc. comprising maintaining a supply of grit at a predetermined point, continuously passing an asphalt coated felt past the point of grit supply, distributing the grit from said supply over the moving surface of the felt, said grit supply being of a predetermined color, replenishing said supply with grit of a blend of substantially said color and a contrasting color, continuing the 80 distribution of the grit over the moving surface of the felt, and subsequently replenishing the supply of grit with grit of substantially the contrasting color. 85

3. The method of preparing roofing for the manufacture therefrom of vari-colored shingles etc. comprising continuously passing an asphalt coated felt past a point of grit application, uniformly applying at said point a predetermined quantity of grit of a defined color, then applying to the succeeding portion of the moving felt a predetermined quantity of grit of a blend of substantially said defined color and a contrasting color, and applying to the succeeding 90 portion of the moving felt a predetermined quantity of grit of substantially the contrasting color. 100
